United States Patent Office

Des. 220,746
Patented May 18, 1971

220,746

TYPE SOLDERING JIG

Robert C. Lokey, Tamal, Calif. (½ Lokey Tool, Inc., 220
Juana Ave., San Leandro, Calif. 94577)

Filed Nov. 5, 1969, Ser. No. 19,961

Term of patent 14 years

Int. Cl. D8—02

U.S. Cl. D8—71

FIG. 1

FIG. 2

FIG. 3

FIG. 1 is a front perspective view of my new design
for a type soldering jig;

FIG. 2 is an end elevational view thereof; and

FIG. 3 is a rear perspective view thereof.

I claim:

The ornamental design for a type soldering jig, sub-
stantially as shown.
